UNITED STATES PATENT OFFICE.

JAMES WARD PACKARD, OF WARREN, OHIO.

DESIGN FOR A CONVERTER-BOX.

SPECIFICATION forming part of Design No. 23,143, dated March 20, 1894.

Application filed January 25, 1894. Serial No. 498,057. Term of patent 7 years.

To all whom it may concern:

Be it known that I, JAMES WARD PACKARD, of Warren, in the county of Trumbull and State of Ohio, have invented and produced a certain new and original Design for Converter Boxes; and I do hereby declare the following to be a full, clear, and exact description of the invention, such as will enable others skilled in the art to which it appertains to make and use the same.

This is a design for a converter box.

In the accompanying drawings:—Figure 1 is a front elevation with parts broken away and in section. Fig. 2 is an end view thereof. Fig. 3 is a rear view.

The leading features of my design are as follows:—First: The box A of approximately U-shape, that is, its sides are straight, as at a , and curved at a' , and from this curved por-

tion the box is extended as at a'' . Second: The box A having the upper edges of its back b extended as at b' . Third: The box A having its back provided with diagonally arranged ribs or extensions C, which taper from their outer ends at the corners of box A to about the center thereof. Fourth: The cover D tapering from its center to its edge and having a flared portion d .

I claim as my invention—

The design for converter boxes, substantially as herein shown and described.

In testimony whereof I have signed this specification in the presence of two subscribing witnesses.

JAMES WARD PACKARD.
